UNITED STATES PATENT OFFICE.

FLOYD P. BRENEMAN, OF HABANA, CUBA.

CENTRIFUGAL BASKET.

Application filed July 7, 1924. Serial No. 724,668.

The present invention relates to improvements in centrifugal baskets and more specifically to an improved basket for use more particularly in connection with low grade 5 sugars.

In the centrifugalling of the fluid mass, the material has a climbing tendency, that is the material in the basket, due to the high velocity of rotation of the basket, tends not 10 only to move out radially against the wall of the basket, but also to rise upwards along the cylindrical wall of the basket. In other words the material has a tendency to creep from the bottom upwards. If the walls of 15 the centrifugal were of infinite height, the mass would spread out on the walls in thickness varying from bottom upwards and getting progressively thinner toward the top. A cross section vertically would resemble a 20 parabola.

In the conventionally used centrifugal, however, there being a limit to the depth of the basket, this climbing tendency is limited by the top curb, so that a cross section shows 25 practically the same thickness at the top as at the bottom.

In the purging of low grade sugar, one frequently finds on stopping the centrifugal when the operation is apparently finished 30 that on the inner surface of the charge is a film or coat of molasses, this coat varying in thickness. In some cases the coat of molasses attains a great thickness and quite a quantity of molasses is left within the 35 sugar. Also when this is observed, it is frequently found that the sugar behind is completely dried, and free of molasses. When the centrifugal is stopped and the sugar discharged, naturally this molasses is 40 discharged with it and again becomes mixed with the sugar to the commercial detriment of the same.

The cause of the formation of this film is considered to be the high initial speed of the 45 machines, and efforts are made in purging of low grade sugar to give the centrifugal a comparatively long time in which to reach final speed. In case of water driven centrifugals, this is accomplished by using 50 fewer nozzles at the start. With electric individual motor drives, a two speed motor has been provided for this purpose. The motor is started in low speed; then later changed to high.

55 It is proposed to improve this condition in purging low grade sugar, by modifying

the shape of the basket. By making the upper diameter of the basket smaller than the lower portion, it is aimed to make the cross section of the mass thinner at the top 60 than at the bottom, and, should molasses separate and come to the inside, it can rise and go through the thin section at the top.

The invention is equally applicable to all 65 types of centrifugal basket and the construction is such as to admit of only a slight variation over commercial baskets as used at the present time in order that the change may be achieved readily and without requiring any alteration in present machinery 70 or methods.

With the foregoing and other objects in view, the invention will be more fully described hereinafter, and will be more particularly pointed out in the claim appended 75 hereto.

In the drawings, wherein like symbols refer to like or corresponding parts throughout the several views:—

Figure 1 is a vertical section through a 80 centrifugal constructed according to the present invention, and

Figure 2 is a vertical section of a conical basket employing the invention.

Referring more particularly to the drawings 85 1 designates the usual casing adapted to collect the molasses which is thrown out by the centrifugal action through the perforated centrifugal wall 2 of the basket which rotates with the power shaft 3. In the instance shown the sugar is allowed to descend through the central opening 4 of the casing when the centrifugal is stopped, this sugar being guided toward the center by the inverted frusto-conical head 5 at the lower 90 end of the basket.

The material is poured in through the opening in the top of the casing in the usual manner and is deflected as by the cone 6 against the side of the centrifugal. Inasmuch as this is undergoing rapid movement the act of separation immediately begins and the greater quantity of the molasses is thrown through the perforated wall of the centrifugal basket, while the mass of sugar 95 is held within this wall and gradually increases in thickness as the action goes on.

Usually a backing screen 7 is provided upon the interior of the cylindrical wall 2 and within the backing screen is a perforated metal screen 8. This interior perforated screen 8 has usually from 400 to 625 holes 100 105 110

per square inch, in accordance with the character of the sugar or other material to be treated. The basket is usually provided at its top with an inwardly projecting curb lying at almost right angles to the axis of the basket and forming a substantial abutment against which the upper end of the sugar column may strike to resist the climbing tendency of the charge as above referred to. The result is that the sugar piles up in a substantially uniform mass or zone along the cylindrical wall of the basket and the sugar packs in very tightly, particularly after the action has been allowed to go on for some time and there is a substantial resistance to the movement of the molasses through this packed sugar.

A film of molasses separates out upon the interior of the sugar column and is troublesome, if not entirely impracticable, to get rid of by present constructions except by the use of the two speed machines and this involves loss of time in the low speed and is also not any too certain in the result.

Now according to the present invention the curb is done away with and a breast section 9 is provided upon the top of the basket, this section sloping upwardly and inwardly or being substantially diagonal and provided with perforations similar to the wall 2 of the basket. Within the breast section 9 is a backing screen 10 and a perforated metal screen 11. The perforated breast section permits of the escape of the molasses at a point higher than the wall 2 and also at a point inwardly of the escape afforded by the wall 2. Inasmuch as the tendency is to climb, however, the film of the molasses upon the interior has free and ready escape through the perforated breast section. The metal screen 11 within the breast section is preferably of finer mesh having 625 to 1,000 holes per square inch in order to effectually check the rising of the sugar or the escape of the sugar through this breast section.

The breast section will extend at an angle from 45 to 60 degrees with respect to the horizontal and this angle is found to provide all of the necessary resistance to climb of the charge afforded by the more or less right angular curb. The breast section is of substantial depth and this takes care of the curbing action. The angle at which the breast section extends provides a substantial check against the rising of the sugar charge and it also allows the charge to grow thinner at the top only very gradually. The result is that the sugar as indicated in Fig-

ure 1 will always be within the upper portion of the breast section leaving a portion of this section open at all times to the climbing film of molasses within. This film will be evacuated through the perforated breast section and escape with the other molasses to the casing 1. The result is a thoroughly purged and dried sugar which can without any bad result be dumped through the bottom opening 4 when the centrifugal is stopped without involving any remixing of the molasses therewith.

Referring to Figure 2 a conical basket 12 is shown which progresses substantially evenly from a wide bottom toward a narrow top portion. In this case the entire wall as it progressively narrows toward the top will interpose a check throughout its height to the creeping or climbing of the charge and the charge will become thinner at the top due to the inclination of the wall. Consequently the film of the molasses will be afforded a constantly better and greater opportunity of escape as it climbs due to the centrifugal action. At the top of the conical basket is also a diagonal breast section 13 also perforated and this section, due to the conical wall need not be so deep.

It will be found that through the use of a basket of this character the sugar will be more uniform and of a better grade than where the molasses film was allowed to subsequently mix therewith. The construction does not involve any particular departure from present centrifugal baskets and can be made to easily replace the curb now a part of the baskets.

It is obvious that various changes and modifications may be made in the details of construction and design of the above specifically described embodiment of this invention without departing from the spirit thereof, such changes and modifications being restricted only by the scope of the following claim.

What is claimed is:—

A centrifugal basket comprising a perforated wall, a perforated breast section above said wall and projecting diagonally inwardly thereof and upwardly therefrom, said wall and said section being provided with backing screens arranged therein and carried thereby, and perforated metal screens carried within both said backing screens, the perforated metal screen in the basket being of substantially 400 to 625 holes per square inch and the perforated metal screen within the breast being from 625 to 1,000 holes per square inch.
